CLAIM

The ornamental design for a screwhead, as shown and described.

DESCRIPTION

FIG. 1 is a top perspective view of a screwhead showing the claimed design;

FIG. 2 is a left side view of the screwhead shown in FIG. 1, the right side view is a mirror image; and,

FIG. 3 is a top view of the screwhead shown in FIG. 1. The broken lines in the figures illustrate the environment of the claimed design and form no part of the claim.
